E. OLDENBUSCH.

BOOK RACK.

APPLICATION FILED DEC. 7, 1910.

Patented Apr. 2, 1912.

UNITED STATES PATENT OFFICE.

ERNEST OLDENBUSCH, OF NEW YORK, N. Y.

BOOK-RACK.

1,022,150.

Specification of Letters Patent.

Patented Apr. 2, 1912.

Application filed December 7, 1910. Serial No. 596,148.

To all whom it may concern:

Be it known that I, ERNEST OLDENBUSCH, a citizen of the United States, and a resident of the city of New York, borough of Brooklyn, in the county of Kings and State of New York, have invented a new and Improved Book-Rack, of which the following is a full, clear, and exact description.

This invention relates to certain improvements in book racks, and more particularly to that type of book-rack disclosed in my previous Patent No. 952,839 granted March 22nd, 1910.

The main object of my present invention is to simplify the joint or connecting means between the base and the end wall so that all of the parts may be made solely of sheet metal and the cost of manufacture thus materially reduced. By forming the book rack in accordance with my present invention, a smaller number of pieces or parts are necessary and thus the work of assembling is reduced and the liability of parts becoming accidentally detached is reduced.

25 A further object of my invention is to provide a better support for the rack, when the ends are folded down.

30 A still further object is to more effectively support the base between the end walls when the book rack is extended to its maximum extent.

Other objects and advantages will be set forth more fully hereinafter and the scope of the invention particularly defined in the 35 claims.

Reference is to be had to the accompanying drawings, forming a part of this specification, in which similar characters of reference indicate corresponding parts in all the 40 figures, and in which—

Figure 1 is a perspective view of a book rack constructed in accordance with my invention; Fig. 2, is a longitudinal section through the book rack. Fig. 3, is a transverse section and Fig. 4 is a perspective view of a portion of the base.

In the book rack illustrated in the accompanying drawings, I provide two end walls 10 and 11 and a base made up of separate 45 extensible members 12 and 13. Each extensible member is formed of two telescoping channels 14 and 15, each formed of sheet metal substantially as illustrated in my previous patent. The most important feature 55 of my present invention relates to the means

for connecting these channels to their respective end walls. To do this, I employ a transversely extending member 16 formed of sheet metal so bent as to present a substantially flat base portion 17 and a tubular portion 18. The base portion 17 forms the bottom of the tubular portion and the latter is approximately semi-cylindrical in form. One lower edge of the sheet metal forming the tubular portion terminates in engagement with the upper surface of the base and at the opposite edge of the tubular portion, the metal forms substantially a right angle 60. The two channels 15 rest upon the upper surface of the base portion 17 and extend transversely through the tubular portion as is indicated particularly in Fig. 2. The ends of the channels are thus concealed inside of the tubular portion and are supported directly on the base. The channels 70 are preferably held in place by solder, not shown. The other two channels of 14 are secured within the other tubular member in exactly the same way. It will thus be seen that the two channels 15 are rigid with each 75 other as are also the two channels 14. 80

Each end wall is formed of sheet metal and at its end edges has flanges bent to form the sockets, which receive the ends of the tubular members. As illustrated, each 85 socket is formed of a substantially semi-circular flange 21 bent to lie at substantially right angles to the end wall and along the periphery of each flange 21 is a marginable flange 22 at right angles to its corresponding flange 21. The flanges 22 extend toward each other and together with the flanges 21 and the end walls 11 form sockets or pockets into which the ends of the tubular members extend. To facilitate the rotation of the tubular members within the 90 sockets recesses 23 and 24 may be cut in the lower corners of the tubular member, as indicated in Fig. 4.

It will be noted that the angle or corner 100 20 on the tubular member constitutes a stop which prevents the end wall from swinging outwardly beyond a vertical position and that the end wall may readily be folded downwardly, so as to lie on top of the channels. The entire book rack, except for the 105 stops and supports hereinafter referred to, is made of only eight pieces of sheet metal, four of which constitute the channels or base proper, two the end walls and sockets 110

and the other two, the tubular members, which connect the channels to each other and connect the channels to the end walls.

For supporting the book rack and preventing the latter from scratching or marring a table or book-case, upon which the book rack may be placed, I provide legs or supports. Each leg as illustrated includes a sheet metal collar 25, encircling a body or core 26 of rubber cork or other suitable material. The screw 27 extends down through each base flange 19 adjacent its ends and into the core. The screws may be placed in position before the parts are assembled and the supports may be readily screwed on afterward. The supports are very easily removed and replaced by new ones, in case they become worn or injured, and they are very inexpensive to manufacture. It will be noted that the supports are not moved during the folding down of the end walls, so that they still act as supports when the book rack is collapsed, which is not the case in the construction shown in my previous patent.

To prevent the channels 15 from being pulled out of the channels 14, I provide suitable stops which include depending flanges 28 on the free ends of the webs of the channels 15. These extend slightly below the lower edges of the channels, as is indicated in Figs. 2 and 3. Each outer channel 14 has a transverse wall 29, soldered thereto, and each of these walls has an upwardly extending tongue 30, which contacts with the corresponding flange 28, when the book rack is extended to the maximum point. Each wall 29 carries a support, which is preferably identical with the supports above referred to. Thus, when the book rack is extended to the maximum position, the book rack is supported not only at its ends but also midway between the ends. This removes any strain on the parts and resists any tendency to bend the channels.

Various changes may be made in the details of construction within the scope of the appended claims without departing from the spirit of my invention.

Having thus described my invention, I claim as new and desire by Letters Patent.

1. A book rack having two parallel book supporting members, a transversely extending tube presenting a substantially flat lower side terminating in a horizontal flange, said tube having apertures in the side thereof above said flange to receive the ends of said members and support them on said flat lower side and an end wall having flanges integral therewith and bent to engage with the ends of said tube to form a pivotal connection therewith.

2. A book rack having two parallel book supporting members, a transversely extending tube of sheet metal and presenting a substantially flat lower side, said tube having apertures in the wall thereof directly above said flat lower side and receiving the ends of said members to support them on said flat lower side and an end wall having flanges bent to engage with the ends of said tube to form a pivotal connection therewith.

3. A book rack having two parallel book supporting members, a transversely extending tube of sheet metal having apertures in the side thereof receiving the ends of said members to support them and an end wall having flanges bent to lie parallel with each other and in engagement with the ends of said tube and each of said flanges having a marginal flange partly encircling said tube whereby said end wall is pivotally secured to said tube.

In testimony whereof I have signed my name to this specification in the presence of two subscribing witnesses.

ERNEST OLDENBUSCH.
